UNITED STATES PATENT OFFICE.

SAMUEL H. GIBSON, OF CLEVELAND, OHIO, ASSIGNOR TO THE FANNER MANUFACTURING COMPANY, OF CLEVELAND, OHIO, A CORPORATION OF OHIO.

SADIRON HOLDER.

1,424,759.

Specification of Letters Patent. Patented Aug. 8, 1922.

Application filed June 7, 1919. Serial No. 302,554.

To all whom it may concern:

Be it known that I, SAMUEL H. GIBSON, a citizen of the United States, residing at Cleveland, in the county of Cuyahoga and 5 State of Ohio, have invented a certain new and useful Improvement in Sadiron Holders, of which the following is a full, clear, and exact description.

This invention relates to a holder for sad irons of the type which in the trade are generally known as Mrs. Potts' sad irons.

The object of the invention is to provide a sad iron holder in which the handle or that portion which is grasped by the hand of the 15 user is so fashioned as to have a certain amount of resiliency.

A further object of the invention is to provide a sad iron handle in which the hand engaging portion is made from a wire coil thus 20 providing a large heat radiating surface so that the handle does not become excessively hot.

A further object of the invention is to provide a construction for a sad iron handle 25 which may be manufactured by simple manufacturing processes, thereby enabling the same to be produced at a low manufacturing cost.

Generally speaking the invention may be 30 said to comprise the elements and the combinations thereof set forth in the accompanying claims.

Reference should be had to the accompanying drawings forming a part of the 35 specification in which Fig. 1 is a side elevation of a sad iron handle embodying my invention; Fig. 2 is a top plan view with the handle portions removed; Fig. 3 is a section upon the line 3—3 of Fig. 2; Fig. 4 is a section upon the line 4—4 of Fig. 2; Fig. 5 is a 40 section upon the line 5—5 of Fig. 2.

Referring to the drawings, 1 indicates a base portion which at its opposite ends is formed with upturned portions 2 and 3. 45 These upturned portions are provided with openings indicated at 2^a and 3^a. The base is formed with an open portion 4 to provide lightness and the base is also provided with another open space indicated at 5 which is 50 adapted for the reception of a latch 6.

Extending across the space 5 and integral with the base is a downwardly extending portion 7 which forms one of the jaws cooperating with the latch for engaging the sad 55 iron. The member 7 as before stated, extends across the space 5 and forms an abut-

ment against which the forward end of the latch may rest.

Adjacent the end of the open portion 5 the base is provided with depressions 8 60 which depressions are adapted to receive side extending arms 9 of the latch. At one end of the latch the same is formed with a downwardly extending portion 10 which lies adjacent the portion 7 before described, the 65 parts 7 and 10 being adapted to receive between them a portion of the sad iron which is to be grasped by the handle.

The latch 6 carries a knob 11 which in the present instance may be made of wood and is 70 secured to the latch in a desired manner as by means of a rivet such as indicated at 12.

The handle proper or hand engaging portion which is generally indicated at 15 is formed by a coiled wire, the convolutions of 75 which are slightly spaced and which is preferably formed to be tapering from a central portion to the ends of the hand engaging portion for the purpose of affording a more ready grasp for the hand of the user. 80

The ends of the hand engaging portion 15 are supported at their opposite ends by means of uprights which are connected with the upstanding portions 2 and 3 of the base 1. 85

Furthermore, the latch 6 is held in the position shown in Fig. 1 by means of a resilient arm or spring member 13, this member engaging with the latch and as shown the latch 6 is provided with a groove 6^a in which 90 the end of the resilient member 13 lies so as to provide a centering arrangement to hold the spring member 13 in proper place upon the latch.

Preferably the hand engaging portion 15, 95 together with the side members 15^a and 15^b as well as the spring member 13 are all formed from a continuous piece of wire. When this is done the end of the portion 15^a is riveted in the opening 2^a of the upstanding portion 2 while the portion 15^b extends through the opening 3^a in the upstanding portion 2 and the end of the wire bears against the latch as indicated in the drawing and as before described. As will be well 100 understood the wire portion which has just been described may be made out of various grades of wire but generally the wire has a fair amount of resiliency in order to provide resiliency in the hand engaging portion 15 as 105 well as in the part 13 which bears against the latch.

The portion 15^b of the wire merely extends through the opening 3^a and is not secured thereto so that under flexure of the portion 13, when the knob 11 is raised, the movement 5 is transmitted from the member 13 to the member 15^b and so to the hand engaging portion 15, although of course a certain amount of movement is absorbed by the portion 13. This construction is made because of the 10 fact that the portion 13 is not subject to repeated flexing which would be likely to cause crystallization and breakage but rather the movement is transmitted to the larger coils of the hand engaging portion 15 where 15 the movement as distributed to the whole of the portion 15 is not sufficient to cause any great amount of flexing and its consequent crystallizing effect.

Attention is called to the fact that the 20 bearing for the rear end of the latch is a comparatively wide bearing, the extension 8 from the latch extending well away from the axis of the latch. This is important in that it reduces the tendency for the latch 6 25 to move in a sidewise direction when the latch is raised and lowered.

Having described my invention, I claim,

1. A sad iron holder comprising a base 30 portion and handle formed as a coil, upright members securing the handle to the base, said upright members and hand engaging portion being formed from a single and continuous piece of wire, a latch member carried by the base, said wire having an extension which engages the latch to hold it in position.

2. A sad iron holder comprising a base, a latch pivoted upon said base, a hand engaging portion formed as a wire coil, an up-

right member securing one end of the coil to 40 the base, and a second upright member formed of resilient material, securing the opposite end of the hand engaging portion to the base and an extension from said last named upright member engaging the latch 45 to hold the same in position.

3. A sad iron holder comprising a base, a latch member pivoted upon said base and a continuous wire member secured at one end 50 of the base and forming an upright and a coiled hand engaging portion and a second upright member which extends through an opening in the base, the end of the wire bearing against the said latch to hold it in position.

4. A sad iron holder comprising a base portion, a latch movably mounted on said base portion, a single piece of wire bent to form upright members and an intermediate portion, said upright members being secured 60 to the base adjacent the ends thereof, one of the said upright members having an extending portion which engages with the latch to hold it in position.

5. A sad iron holder comprising a base 65 portion, a latch movably mounted on the base portion, a wire secured at one end to the base portion and bent to form an upright end member, a handle extending substantially parallel with the base, a second 70 upright member which passes through an opening in the base and an extending portion which engages with the latch to hold the same in position.

In testimony whereof, I hereunto affix my 75 signature.

SAMUEL H. GIBSON.
